UNITED STATES PATENT OFFICE.

GEORGE E. MOLYNEUX, OF BAYONNE, NEW JERSEY, ASSIGNOR TO UNITED SHOE MACHINERY CORPORATION, OF PATERSON, NEW JERSEY, A CORPORATION OF NEW JERSEY.

ART OF MANUFACTURING BOOTS AND SHOES.

Application filed September 18, 1922. Serial No. 588,860.

To all whom it may concern:

Be it known that I, GEORGE E. MOLYNEUX, a citizen of the United States, residing at Bayonne, in the county of Hudson and the State of New Jersey, have invented certain Improvements in Art of Manufacturing Boots and Shoes, of which the following description, in connection with the accompanying drawings, is a specification, like 10 reference characters on the drawings indicating like parts in the several figures.

This invention relates to a boot or shoe and the method of making it.

Shoes most commonly in use comprise a lining of fabric and an upper of leather; and usually the upper and the lining, each consisting of several parts stitched together, are assembled by being stitched together and then this composite member is placed, together with a sole or an insole, upon a last and the manufacture of the shoe completed, the particular manner of attaching the upper to the sole or insole depending upon whether the shoe is to be of the turned, McKay, Goodyear welt, Stitchdown, or other type. In any event, the upper, which, as has been stated, is commonly of leather, is made of several pieces of sheet material cut to the proper size and shape and stitched or otherwise fastened together. Leather is an expensive material; and skilled labor is required to make the patterns, cut the leather pieces, fasten them properly together and incorporate the leather upper in a shoe.

According to the present invention, no leather or other sheet material is used in making the upper. Instead, the shoe is made up to a certain point in the usual manner except that no upper is provided; and the exposed lining, which is preferably of a special fabric, is covered with a liquid having contained therein a substance which upon evaporation of the liquid leaves a coating of tough, flexible material on the lining. This coating may be applied at any suitable stage in the manufacture of the shoe after the lining has been lasted. In the manufacture of the particular welt shoe herein described, it is applied after the sole has been attached and rough rounded.

Referring now to the accompanying drawings:

Fig. 1 shows a shoe, substantially complete except for the upper and the heel, in process of having grease applied to the welt and sole so as to prevent the coating material subsequently to be applied from adhering to these members.

Fig. 2 shows the shoe in process of being 60 coated.

Fig. 3 shows the coated shoe standing upon a rack to permit the coating to set, and

Fig. 4 shows the completed shoe. 65

The drawings illustrate a shoe of the Goodyear welt type; but the type of shoe, as will presently appear, is immaterial so far as the broader aspects of the invention are concerned. The lining 5 is made like 70 an ordinary lining but of specially woven fabric in which the capability of stretching is substantially the same in two directions. For example, a cotton fabric such as that used in the manufacture of automobile tires 75 may be employed. It is desirable that the fabric possess this capability, so that substantially all of the stretch may be taken out of it during the pulling over and lasting operations, and that it possess great 80 strength. The layer of coating material 7 which is caused to adhere to it and forms the upper of the finished shoe does not possess the strength of leather or the other materials now commonly used; and it is therefore desirable that the lining or foundation 85 of the finished shoe be strong and practically incapable of stretching.

After the lining or foundation 5 has been made, with suitable pockets if desired for the reception of the box toe stiffener 9 and counter stiffener 11, the lining with the stiffener is placed together with an insole 13 upon a last 15. Before, however, the assembling of these parts upon the last takes 90 place, those portions of the last which will be exposed after the lasting of the lining has been completed are covered with oiled silk 17 or some suitable material or substance which will prevent the liquid, later 95 to be sprayed upon the shoe, from reaching the last. The exposed portions of the last, 100

in the illustrated construction, are the extreme upper portion and a narrow area extending down the front of the last.

After the lining and insole have been assembled on the last, the free edges of the lining (that is the top edge of the lining and the edges along the opening in the front of the lining) are fastened to the last as for example by tacks 19, the purpose of this temporary fastening being to hold the lining against the strain of the pulling-over and lasting operations so that it will be stretched to its uttermost. The lining is now pulled over and lasted, care being taken to remove substantially all the stretch of which the original fabric was capable, after which the welt 21 and outsole 23 are attached in the usual manner and the sole rough rounded. At this point the lining or foundation 5 is cleaned to remove all dirt and grease and is shrunk. Benzine, or benzine and water may be used for this purpose. If, after the lining has been cleaned and dried, any wrinkles appear these may be moistened and ironed out with a hot tool. The bottom of the sole, the edges of the sole and welt (and the top of the welt if so desired) are next coated with grease or otherwise covered to prevent the sprayed material from adhering to them.

The shoe thus partly made is then subjected to a spray of coating material. To this end the shoe may be placed upon a turn-table 25, which is rotated in any suitable manner while the coating material 27 is sprayed upon it. Considerable force is used so as to embed the first portion of the coating material in the interstices of the fabric which have been more or less opened by the stretching to which the fabric has been subjected. The coating material may consist of any suitable substance such, for example, as a solution of one of the esters of cellulose with the addition of castor oil or of some similar substance to render the final coating more pliable. For example, 8 ounces of nitro-cellulose and 8 ounces of castor oil may be dissolved in one gallon of liquid made up of benzol 60%, ethyl alcohol 20%, butyl acetate 10%, and ethyl acetate 10%.

After the coating has reached the desired thickness, the edge and bottom of the sole are wiped off and the coated shoe hung up by a hook 29 or placed upon the bars 31 of a rack and allowed to stand until the solvent has evaporated and the coating has set or seasoned, heat being employed, if desired, to hasten the process. The tacks are pulled out and the last removed from the shoe. The tack holes are very small and in most cases not objectionable. They may, however, be covered by facings if desired. The eyelet stays are next sewed on, and the shoe finished including setting the eyelets,

attaching the heel and finishing the edges of the sole and heel.

Although the article has been described in connection with the manufacture of a particular shoe and the method as being carried out by steps in a given order, it should be understood that the invention is not limited to the particular shoe nor to the particular order of the steps.

Having thus described my invention, what I claim as new and desire to secure by Letters Patent of the United States is:—

1. The method of manufacturing a shoe which comprises assembling a lining and a bottom member upon a last, drawing the lining tightly about the last and spraying upon the lining a coating substance to form the upper.

2. The method of manufacturing a shoe which comprises assembling a lining and a bottom member upon a last, fastening to the last the top edge and the edges along the opening in the front of the lining, drawing the lining tightly about the last while it is so fastened and thereby stretching it thoroughly, and spraying upon the lining a coating substance to form the upper.

3. The method of manufacturing a shoe which comprises making the shoe including a lining substantially complete except for the upper and then spraying upon the exposed lining a liquid having contained therein a substance which upon drying leaves a tough, flexible coating adhering to the lining.

4. The method of manufacturing a shoe which comprises preparing a lining of fabric in which the capability of stretching is substantially the same in at least two directions, assembling the lining together with a bottom member upon a last, fastening to the last the upper edges of the lining, exerting a pull upon the lining while it is so fastened sufficient to stretch it substantially to its uttermost, and thereafter completing the manufacture of the shoe including applying to the stretched lining a coating of upper material.

5. The method of manufacturing a shoe which comprises preparing a lining of fabric in which the capability of stretching is substantially the same in at least two directions, assembling the lining together with a bottom member upon a last, fastening to the last the upper edges of the lining, exerting a pull upon the lining while so fastened sufficient to stretch it substantially to its uttermost, and thereafter completing the manufacture of the shoe including spraying upon the stretched lining a liquid having contained therein a substance which upon drying leaves a coating of upper material on the lining.

6. The method of manufacturing a shoe which comprises covering the top and front

- of a last with a protective material, assembling upon the last a fabric lining and a bottom member, drawing the lining tightly about the last and fastening it to the bottom member, spraying a coating substance upon the shoe to form an upper, removing the last and completing the manufacture of the shoe.
7. The method of manufacturing a shoe which comprises assembling a lining and an insole upon a last, drawing the lining about the last and attaching it to the insole, attaching an outsole, applying a covering of an oily nature to the edge and bottom of the outsole, spraying upon the shoe a liquid material adapted upon drying to form a tough coating, wiping off the edge and bottom of the outsole, removing the last and completing the manufacture of the shoe.
8. The method of manufacturing a shoe which comprises assembling a lining and a bottom member upon a last, drawing the lining tightly about the last and spraying upon the lining a liquid having contained therein a substance which upon evaporation 25 of the liquid leaves a flexible coating adhering to the lining.
9. The method of manufacturing a shoe which comprises assembling a lining and a bottom member upon a last, fastening to 30 the last the top edge and the edges along the opening in the front of the lining, drawing the lining tightly about the last while it is so fastened and thereby stretching it thoroughly, and spraying upon the lining a liquid 35 having contained therein a substance which upon evaporation of the liquid leaves a flexible coating adhering to the lining.
10. The method of manufacturing a shoe which comprises assembling a lining and a bottom member upon a last, drawing the lining tightly about the last and spraying upon the lining a solution of a cellulose ester.

In testimony whereof I have signed my 45 name to this specification.

GEORGE E. MOLYNEUX.
